UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

LOCKER LOCK.

Application filed March 24, 1921. Serial No. 455,030.

To all whom it may concern:

Be it known that I, WALTER N. VANCE, a citizen of the United States, residing in Chicago Heights, in the county of Cook and State of Illinois, have invented a new and useful improvement in Locker Locks, of which the following is a specification.

My invention relates in general to doors and has more particular reference to locking devices therefor especially adapted for use upon lockers and the like which it is desired shall be accessible to more than one individual.

In business establishments where individual lockers are furnished for employees it is frequently desirable to have the employees furnish their own locks in order to relieve the employer from responsibility and annoyance in supplying extra keys. At the same time, the employer may wish to have access to the lockers at will without calling upon the employees for their keys. Similarly in schools and like institutions, it may be desirable for certain authorities to have access to lockers independently of the users thereof.

It is, therefore, a principal object of my invention to provide a locking device whereby such a door may be unlocked through the instrumentality of separate locks, each adapted to permit opening of the door independently of the other.

A further object of the invention is the provision of a locking device of the character mentioned, which locks the door firmly through the use of a minimum number of operating parts, each of said parts being simple in construction and durable in service.

Still further object of the invention is the provision of independently acting locks so arranged as to present a pleasing appearance and to render unostensible the object for which they are used.

Another object of the invention is the provision of a locking device which may be used upon practically any type of locker door or equivalent without material change in the general construction thereof.

Still another object of the invention is the provision of a door having a locking device of the kind described which is dependable in action and susceptible of practical and inexpensive production as an article of manufacture.

Other objects and advantages of the invention will be apparent as it is better understood from the following description when considered in connection with the accompanying drawings illustrating a preferred embodiment thereof.

Referring to the drawings:

Figure 1 is a fragmentary perspective view of a section of lockers showing one complete front or door;

Fig. 2 is a fragmentary elevational view of the interior of a door showing the locker casing in section;

Fig. 3 is an enlarged section taken substantially on the line 3-3 in Fig. 1, showing the lock staples closed;

Fig. 4 is a similar section showing the lock staples in open position;

Fig. 5 is an enlarged schematic view of one of the door straps and a section of the sliding bar showing means of engagement therewith;

Fig. 6 is a section taken substantially on the line 6-6 in Fig. 3; and

Fig. 7 is a perspective view of a lock plate and receiving staple.

On the drawings which illustrate a preferred embodiment of my invention, the reference numeral 11 indicates a locker frame as a part of a tier of lockers fragmentarily shown. A door 12 is secured upon hinges 13 to the front casing 14 of the locker. This door is opened and closed by means of a handle 15 rigidly secured to a sliding locking bar 16. This bar is secured to the casing 14 by means of rivets 17 taking through slots 18 in said bar. The bar is deformed at intervals to provide inwardly projecting sections 19 from the top of which V-shaped lugs or offsets 21 are cut and arranged in vertical alignment with the straight portions of the bar.

Straps 22 are secured by means of rivets 23 to the locker casing and extend over the inwardly extending door flange 24, to which the locking bar 16 is slidably secured. In each strap 22 is a V-shaped recess 25 adapted to engage the depending lug 21 when the door is closed and locked.

Integral with the handle 15 is a locking staple 26 which, of course, moves only with the bar 16, the handle 15 being rigidly secured to said bar by integral straps 27 riveted at 28 to said bar, and said straps being slidable in recesses 30 in the door. Usually

it has been the custom to lock the bar 16 to some permanently fixed part of the door to lock the locker. Instead of so locking it, however, I provide a plate 29, having secured in a recess 40 therein a receiving staple 31 into which the staple 26 is received and to which it may be secured by a padlock 32. This staple is held in place by means of overturned back flanges 30' and offset outer flanges 31' engaging the material of the plate 29. This plate is slidably attached to the exterior of the door and is free to move vertically except as restrained by a bolt 33 of a rim lock 34. A rivet 35 extends through an aperture 36 in the plate 29 and through a recess 37 in the door, the inner end of said rivet being in the form of a block 38 slidable within the door.

The lock 34 may be of any preferred type 20 and it will be understood that a combination lock might be used in the place of the rim lock shown in the drawings. It has been found that an ordinary cylinder rim lock is entirely satisfactory for the purpose.

25 When both the locks are locked it will be impossible either to move the staple 26 and, with it, the bar 16 independently of the plate 29 or to move said plate vertically with said staple 26 and bar 16. The door, therefore, will be locked in closed position since the lugs 21 cannot be removed from the recesses 25. If the padlock be removed, the staple 26 may be freely moved even though the plate 29 remain in fixed position, and the bar 16 may be raised to permit opening of the door. If the padlock 32 be locked in place, the door may nevertheless be opened by unlocking the rim lock 34 to permit vertical movement of the plate 29 with the staple 26, whereby the bar 16 may be raised as heretofore described.

It is obvious that in this manner the locker may be rendered accessible to either the possessor of a key for the padlock 32 or for the 45 rim lock 34, the cooperation of the two locks being necessary to hold the door in locked position.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A front for lockers and the like, comprising a door, a door casing, a slideable latching bar in said door, a handle fixedly secured to said bar, keeper members on said casing adapted to cooperate with said bar to latch the door closed, and a plurality of locks for locking said bar in latching posi-

tion, the operation of a single lock releasing the bar to unlock the door.

2. A front for lockers and the like, comprising a door, a door casing, a slideable latching bar in said door, a handle fixedly secured to said bar, keeper members on said casing adapted to cooperate with said bar to latch the door closed, and a plurality of locks, for locking the door, said latching bar and keeper member being disengaged by removal of one of said locks.

3. A front for lockers and the like, comprising a door, a door casing, a slideable latching bar in said door, a handle fixedly secured to said bar, keeper members on said casing adapted to cooperate with said bar to latch the door closed, a fixed staple on said bar and protruding from said door, a slideable plate positioned exteriorly on the door and having a staple receiving portion 85 together adapted to receive said fixed staple, a padlock for locking said staple and staple receiving portion, and a second lock adapted to prevent vertical movement of said plate, whereby said door may be unlocked by either lock.

4. A front for lockers and the like, comprising a door, a door casing, a latching bar slideably secured to said door and having projecting latching lugs, a handle fixedly secured to said bar, recessed straps secured to said casing and adapted to cooperate with said lugs to latch the door closed, and a plurality of locks, for locking said bar in latching position, the operation of a single 100 lock releasing the bar to unlock the door.

5. A front for lockers and the like, comprising a door, a door casing, cooperating latching members secured respectively to said door and casing, and a plurality of locks for locking said latching members, the operation of any one lock releasing said latching members to unlock the door.

6. A front for lockers and the like, comprising a door, a door casing, a latching bar 111 slideably secured to said door, a handle fixed upon said bar and extending outwardly from said door, cooperating keeper members secured to said casing and engaging portions of said bar, a staple integral with said handle, a slideable plate positioned exteriorly of the door and having a staple receiving portion adapted to receive and be locked to said handle staple, a padlock for locking said staple parts together, and a second lock adapted to prevent vertical movement of said plate, whereby to permit opening of said door by unlocking either of said locks.

7. In combination with a locker, having 125 a door and a door casing, a locking device comprising a latching bar slideably secured to said door and having projecting locking lugs, cooperating keeper members secured to said casing and adapted to engage said 130

lugs when in locked position, a handle rigidly secured to said bar, a slideable plate positioned exteriorly of the door, and a plurality of locks, one being adapted 5 to lock said plate and handle together and the other to prevent vertical movement of said plate, whereby the door may be opened by locking either of said locks.

8. In combination with a locker having 10 a door and a door casing, a slideable latching member and a fixed keeper member, one of said members being attached to said door and the other to said casing, a sliding member to which said slideable latching member 15 may be locked, a lock for locking said members together, and a second lock for restraining sliding movement of said sliding member, whereby said locks must cooperate to prevent opening said door.
- 20 9. In combination with a locker having a door and a door casing, a slideable latching member and a fixed keeper member, one of said members being attached to said door

and the other to said casing, a sliding member to which said slideable latching member 25 may be locked, a lock for locking said members together, and a second lock for restraining sliding movement of said sliding member, whereby said locks must cooperate to prevent opening said door, one of said 30 locks being a rim lock and one a padlock.

10. A locker, comprising a frame, a door, co-operative latching devices positioned respectively on said frame and door, and a plurality of locks for locking said latching 35 devices, the operation of any one lock releasing said devices to unlock the door.

11. A locker, comprising a frame, a door, a keeper on the frame, a movable locking member on the door, and a plurality of locks 40 for locking said member in engagement with said keeper, the operation of a single lock permitting disengagement of said parts to open the door.

WALTER N. VANCE.
